a corporation of New York

Application December 28, 1948, Serial No. 150,399

Term of patent 14 years

(Cl. D87—3)

To all whom it may concern:

Be it known that I, Herbert Chase, a citizen of the United States, residing at 138-62 67th Road, city of New York, county of Queens, and State of New York, have invented a new, original, and ornamental Design for a Wallet or Similar Article, of which the following is a specification, reference being had to the accompanying drawing, forming part thereof.

Fig. 1 is a perspective view of the front of the wallet in a closed condition.

Fig. 2 is a perspective view of the rear of the wallet in a closed condition.

Fig. 3 is a perspective view of the inside of a wallet or similar article in an open position, with the coin-retaining element extended.

Fig. 4 is a perspective view similar to Fig. 3 but showing the opposite side to that shown in Fig. 3.

I claim:

The ornamental design for a wallet or similar article, substantially as shown and described.

HERBERT CHASE.
